(57) **CLAIM**

The ornamental design for a display screen or portion thereof with animated graphical user interface, as shown and described.

DESCRIPTION

FIG. 1 is the first image in a sequence for a display screen or portion thereof with animated graphical user interface showing our new design;

FIG. 2 is the second image thereof; and,

FIG. 3 is the third image thereof.

The appearance of the animated graphical user interface sequentially transitions between the images shown in FIGS. 1-3. The process or period in which one image transitions to another forms no part of the claimed design.

The outermost rectangle shown in broken lines illustrates the display screen or portion thereof; the remaining broken lines illustrate portions of the animated graphical user interface. The broken lines form no part of the claimed design.
